UNITED STATES PATENT OFFICE.

OWEN OSBORNE, OF PHILADELPHIA, PENNSYLVANIA.

DESIGN FOR A STOCKING.

SPECIFICATION forming part of Design No. 30,074, dated January 24, 1899.

Application filed December 21, 1898. Serial No. 699,971. Term of patent 7 years.

● *To all whom it may concern:*

Be it known that I, OWEN OSBORNE, a citizen of the United States, residing in Philadelphia, Pennsylvania, have invented a certain new and useful Design for a Stocking, of which the following is a specification.

My design is fully shown in the accompanying drawing.

The stocking has a foot knitted in plain stitch and a leg knitted in rib-stitch and also having in addition to the longitudinal rib-wales a multiplicity of fine transverse ribs extending throughout the ankle, calf, and top portions of the leg, said plain foot, rib-stitch leg, and transverse ribs in the leg portion constituting the essential features of the design.

In the drawing, 1 represents the plain-stitch foot of the stocking, 2 the rib-stitch leg, and 3 the transverse ribs of the latter.

Having thus described my invention, I claim and desire to secure by Letters Patent—

The design for a stocking, substantially as described and shown in the accompanying drawing.

In testimony whereof I have signed my name to this specification in the presence of two subscribing witnesses.

OWEN OSBORNE.
